UNITED STATES PATENT OFFICE.

WILLIAM R. WILLETTS, OF WATERBURY, CONNECTICUT, ASSIGNOR TO AMERICAN PIN COMPANY, OF WATERBURY, CONNECTICUT, A CORPORATION OF CONNECTICUT.

DESIGN FOR A BOWL FOR WASTE-WATER TRAPS.

40,780.

Specification for Design.

Patented July 19, 1910.

Application filed December 3, 1909. Serial No. 531,261. Term of patent 14 years.

To all whom it may concern:

Be it known that I, WILLIAM R. WILLETTs, a citizen of the United States of America, residing at Waterbury, in the county of New Haven and State of Connecticut, have invented a new, original, and ornamental Design for a Bowl for Waste-Water Traps, of which the following is a specification, reference being had to the accompanying drawing, forming a part thereof, in which—

Figure 1 is a side elevation of a bowl for waste water traps showing my new design. Fig. 2 is a plan view.

I claim:

The ornamental design for a bowl for a waste water trap as shown.

WILLIAM R. WILLETTs.
